CLAIM

The ornamental design for a greeting card support device, as shown and described.

DESCRIPTION

FIG. 1 is a side perspective view of a first embodiment of a greeting card support device in a partially open position showing my new design;

FIG. 2 is a top and bottom plan view thereof;

FIG. 3 is a rear view thereof;

FIG. 4 is a side view thereof;

FIG. 5 is an open view of the inside portion thereof;

FIG. 6 is a side perspective view of another embodiment of a greeting card support device in a partially open position showing my new design;

FIG. 7 is a top and bottom plan view of that shown in FIG. 6;

FIG. 8 is a rear view of that shown in FIG. 6;

FIG. 9 is a side view of that shown in FIG. 6; and,

FIG. 10 is an open view of the inside portion of that shown in FIG. 6.
